(57) **CLAIM**

The ornamental design for a surgeon interactive display screen with a graphical user interface, as shown and described.

DESCRIPTION

FIG. 1 is a front view of a first embodiment of a surgeon interactive display screen with a graphical user interface; and,

FIG. 2 is a second embodiment thereof.

The broken lines showing the display screen form no part of the claimed design. The remaining broken lines showing portions of the graphical user interface form no part of the claimed design.

1 Claim, 2 Drawing Sheets
